US00D864128S

(12) **United States Design Patent** (10) **Patent No.:** **US D864,128 S**
Ferdinand et al. (45) **Date of Patent:** **** Oct. 22, 2019**

(54) **REMOTE CONTROL**

(71) Applicant: **FM MARKETING GMBH**, Neumarkt am Wallersee (AT)

(72) Inventors: **Maier Ferdinand**, Neumarkt am Wallersee (AT); **Erwin Weitgasser**, Salzburg (AT)

(73) Assignee: **fm marketing gmbh**, Neumarkt am Wallersee (AT)

(**) Term: **15 Years**

(21) Appl. No.: **35/504,864**

(22) Filed: **Jul. 25, 2017**

(80) **Hague Agreement Data**

Int. Filing Date: **Jul. 25, 2017**

Int. Reg. No.: **DM/100697**

Int. Reg. Date: **Jul. 25, 2017**

Int. Reg. Pub. Date: **May 4, 2018**

(30) **Foreign Application Priority Data**

Feb. 24, 2017 (EM) 003765445

(51) **LOC (12) Cl.** **14-03**

(52) **U.S. Cl.**

USPC **D13/168**

(57) **CLAIM**

The ornamental design for a remote control, as shown and described.

DESCRIPTION

1.-3. Remote controls

1.1 front elevation view

1.2 left elevation view

1.3 rear elevation view

1.4 front perspective view

1.5 top plan view

1.6 bottom plan view

1.7 right elevation view

1.8 rear perspective view

2.1 right elevation view

2.2 left elevation view

2.3 top plan view

2.4 front perspective view

2.5 front elevation view

2.6 rear elevation view

2.7 bottom plan view

2.8 rear perspective view

3.1 top plan view

3.2 bottom plan view

3.3 right elevation view

3.4 left elevation view

(Continued)

3.5 rear elevation view
3.6 front elevation view

1 Claim, 22 Drawing Sheets**(58) Field of Classification Search**
